CRANKSHAFT MAIN JOURNAL GRINDER

Fred Robert Henderson, Kansas City, Mo.

Application June 7, 1951, Serial No. 230,397

2 Claims. (Cl. 51—241)

1

This invention relates to apparatus for grinding main journals of a crank shaft while the crank shaft remains in the engine block of a motor car or truck.

Heretofore apparatus has been used for grinding connecting rod journals by clamping the device about the journal and allowing it to move up and down in the engine block while the journal is being ground but this apparatus is not suitable or applicable to grinding the main journals. Another device has been used for adjusting the apparatus for grinding the connecting rod journals at right angles to the longitudinal axis of the crank shaft by tilting the grinding apparatus on the connecting rod journal. Another device is a grinding apparatus rigidly bolted to the connecting rod with the connecting rod clamped against the journal in a rigid and unadjustable manner with respect to alignment of the grinding apparatus on its crankshaft journal.

An object of the present invention is to provide a grindstone mounted on a shaft in a frame fulcrumed on an elongated support parallel therewith and have a flexible and adjustable means of coupling to the main journal bearing flange, the bearing liner being removed and an adjustment provided for aligning and holding the grindstone shaft at right angles to the longitudinal axis of the crank shaft.

With these main objects in view the invention is more fully understood from the drawings, the following specification and the scope of the claims appended.

In the drawings.

Figure 1 illustrates a fragment of an engine block in a motor car or truck, a cross section of a main journal with the lower bearing cap and liners removed, and an elevation of the present grinding apparatus, the coupling and adapter parts being broken to show the interior thereof.

Figure 2 is an elevation of the elongated support member turned at 90 degrees on its longitudinal axis from that illustrated in Figure 1.

Figure 3 is a bottom view illustrating the anchor stirrup and adjustment connected to the elongated support member, the bottom of the motor being attached to the elongated member showing the limit means for fulcrum movement of the motor and grindstone shaft.

Figure 4 is a fragmentary bottom view of a crank shaft mounted in an engine block with the bearing liners and cap removed from the main journal, the adapter plate being bolted to the bearing flange and the support coupling at-

tached. A grindstone is illustrated on the journal.

Figure 5 illustrates a side elevation of a main journal bearing frame with the lower cap and liners removed and a fragment of the elongated support member attached to the adapter plate.

support member attached to the adapter plate. Figure 6 is an elevation of the coupling used for anchoring and supporting the elongated support member.

Figure 7 shows the end of the coupling having an internal thread for connection of the elongated support member.

Figure 8 is a view illustrating the adapter plate having a tapped hole in the center thereof and bolt or cap screw slots at each end thereof.

The engine block 9 usually remains in the main frame 10.

20 The engine block 9 usually remains in the motor chassis and has the usual crank case and selected main bearing cap with liners removed, the removed items are not illustrated because of their well known construction and their removal for the use of the present apparatus. The engine block 9 has the journal bearing upper cap 10 integral therewith and is usually provided with two holes 11 on each flange 12 of the cap 10. An adapter plate 13 is preferably of a rectangular shape and thick enough for sufficient threads 14 tapped therein to receive and hold a coupling 15 consisting of a threaded shank 16, cap 17, and eccentric tapped thread 18. This eccentric coupling 15 supports the upper threaded end 19 of the elongated support member 20, and a hinge 21 on the lower end of support member 20 is provided to connect to the lower portion of the elongated member 22. A lock nut 23 locks the shank 16 of the eccentric coupling against the adapter plate 13 and cap screws 24 hold the adapter plate 13 against the upper bearing cap flange 12.

The elongated support member 22 is preferably round and has fulcrumed thereon arms 25 and 26 at 27 and 28. The arms 25 and 26 are joined to a frame 29 which contains and supports an extension shaft 30 on an electric motor 31, the extension shaft 30 being coupled to the motor shaft 32 by coupling 33. The upper end of the extension shaft 30 is provided with an attached grindstone 34. The grindstone 34 is preferably a cylindrical shape and has a flat face 35 bearing against the journal 36 by means of screw pressure but the movement thereof toward the crank shaft is limited by the micrometer adjustment 37 engaging threads 38 on the corners of the squared shaft 39 of the elongated member 22.

The squared shank 39 rigidly holds the boss 55 40 of arms 41 against rotation and receives the

limit screws 42 adapted to bear against the limit lug 43 of the electric motor 31.

The coil compression spring 44 is mounted on the elongated member 22 between the anchored collar 45 and sliding collar 46, bearing against the fulcrumed arm 26 which is slidable on the elongated support member 22.

The flange 47 of the engine block 9 has a stirrup shaped bar 48 cap screwed thereto by cap screws 49, and the extended arms 50 thereof are provided with adjustment holes 51 to receive cap screws 52 passing therethrough into the tapped threads 53 of the connecting arms 54. The connecting arms 54 have a threaded adjusting rod 55 mounted therein and is turned by thumb knob 56. A guide rod 57 is mounted between the connecting arms 54 and a guide member 58 slides thereon. The threaded rod 55 passes through the tapped hole 59 in the guide member 58 and a slot 60 is provided in the outer end of the guide member 58 to receive the elongated support member 22.

Figure 5 differs with Figure 1 in that it is a modified view illustrating the elongated support member being screwed into the adapted plate 13 and the lock nut 23 holding it in a locked position. This modified view of Figure 5 eliminates the eccentric coupling only when one make of engine blocks are used, however, the eccentric coupling is necessary for various makes of engine blocks because of the different centers between cap screws of the main bearings.

In the use of the present device the engine preferably remains in the chassis and the crank case and lower bearing cap with liners are removed. The adapted plate 13 is cap screwed to one of the flanges of the upper cap and either the eccentric coupling 15 or an extended shaft 20 is screwed into the cap threads 14. The lock nut 23 may be used to lock the coupling 15 or an extension of the shaft 20 as a modified form. The coupling 15 also provides for different diameters of tapped threads.

The shaft or upper elongated support member 20 may be replaced at the hinge point for different diameters of attachment when necessary and the object of the hinge is to allow the motor with shaft fulcrumed on the elongated support member 22 to move on the hinge and be held in position by guide member 58. This guide member is moved longitudinally with respect to the longitudinal axis of the crank shaft by means of the screw 55 and thumb nut 56. The arms 54 support the screw and are connected to stirrup extended ends 50, the crank case flange 47 rigidly holding the stirrup by means of the cap screws 49.

What I claim as new and desire to secure by Letters Patent is:

1. Main journal grinding apparatus for an engine block in a motor car having a crank shaft

mounted in the engine with the cap removed from the journal to be ground, comprising, an eccentric coupling, means for connecting the eccentric coupling to the block bearing flange, a shaft, a grindstone, a frame, said shaft passing through said frame and receiving the grindstone on the end thereof, an elongated support member, one end of said support member being connected to said eccentric coupling, a hinge, said hinge being in said support member below said eccentric coupling, said support member being spaced parallel with said shaft, means to support said frame on said support member, means to fulcrum said frame on said support member, means to limit the movement of said frame on said support member, a member having a slot in the end thereof adapted to slide longitudinally on said support member and co-operate therewith as a guide to adjust the support member on said hinge, means to move and hold said member with the slot in the end thereof lengthwise with respect to the crank shaft to adjust the support member with shaft and grindstone at right angles to the axis of the crank shaft, and means to rotate said shaft.

2. Main journal grinding apparatus for an engine block in a motor car having a crank shaft mounted in the engine with the cap removed from the journal to the ground, comprising, a coupling, means for connecting the coupling to the block bearing flange, a shaft, a grindstone, a frame, said shaft passing through said frame and receiving the grindstone on the end thereof, an elongated support member, one end of said support member being connected to said coupling, a hinge, said hinge being in said support member below said coupling, said support member being spaced parallel with said shaft, means to support said frame on said support member, means to fulcrum said frame on said support member, means to limit the movement of said frame on said support member, a member having a slot in the end thereof adapted to slide longitudinally on said support member and co-operate therewith as a guide to adjust the support member on said hinge, means to move and hold said member with the slot in the end thereof lengthwise with respect to the crank shaft to adjust the support member with the shaft and grindstone at right angles to the axis of the crank shaft, and means to rotate said shaft.
